UNITED STATES PATENT OFFICE.

CHALMER DENNY, OF SORENTO, ILLINOIS.

SUBSOIL-PLOW.

1,295,281.

Specification of Letters Patent. Patented Feb. 25, 1919.

Application filed August 31, 1918. Serial No. 252,160.

To all whom it may concern:

Be it known that I, CHALMER DENNY, a citizen of the United States, residing at Sorento, in the county of Bond and State of Illinois, have invented new and useful Improvements in Subsoil-Plows, of which the following is a specification.

This invention relates to sub-soil plows and it consists in the novel features herein-
10 after described and claimed.

An object of the invention is to provide a plow of the character stated which is of simple and durable structure and which is adapted to be used for breaking up the soil
15 for a considerable distance below the normal surface thereof.

With this object in view the plow comprises a wheel mounted body having an engine located thereon and a frame mounted
20 for movement vertically upon said body. Means are provided for raising and lowering the frame with relation to the body. Vertically disposed shafts are carried by the frame and the said shafts in turn are pro-
25 vided with auger blades and cutting elements. Means are provided for rotating the shafts simultaneously from the engine and the shafts at the opposite sides of the body and frame rotate in opposite direction where-
30 by the soil engaging elements operate through the soil in opposite direction and consequently any tendency to side draft or movement is eliminated.

In the accompanying drawing:—
35 Fig. 1 is a top plan view of the plow.
Fig. 2 is a side elevation of the same.
Fig. 3 is a rear elevation of the same.
Fig. 4 is a detail vertical sectional view
of the same.

40 Fig. 5 is a detail vertical sectional view, showing one of the worms 9 and its connected part in elevation.

The plow comprises a body 1 which is mounted upon wheels 2 in a usual manner. An engine 3 is mounted upon the body 1 and is operatively connected with a shaft 4 journaled on the said body by means of a belt 5. Vertically disposed rack bars 6 are mounted at the corner portions of the body
45 1 and a frame 7 is mounted upon the body and provided with guides 8 adapted to move along the rack bars 6. Worms 9 are located between the guides 8 and are slidably mounted on vertically disposed shafts 10 journaled upon the body adjacent the rack bars 6.

The shafts 10 may be provided at their upper ends with crank handles 11. While the worms 9 are slidably mounted upon the shafts 10 they are constrained to rotate with the shafts and the worms mesh with the teeth of the rack bars 6. Beveled pinions 12 are mounted at the lower end of the shafts 10 and mesh with similar pinions 13 mounted upon the end portions of the shafts 14 and the said shafts extend transversely under the body 1 and across the same.

Consequently it will be seen that by rotating either of the shafts 10 the worms 9 at the opposite sides of the machine will be rotated and as they move through the spaces between the teeth of the rack bars 6 the frame 7 will be raised or lowered.

A vertically disposed shaft 15 is journaled for rotation at the forward portion of the body and a pulley 16 is mounted on the said shaft 15. A pulley 17 is mounted upon the shaft 4 hereinbefore described and a belt 18 is trained around the pulleys 16 and 17. Therefore means are provided for rotating the shaft 15 from the shaft 4. A yoke 19 is slidably mounted on the shaft 15 and a gear wheel 20 is journaled for rotation upon the said yoke. The shaft 15 passes through the center of the gear wheel 20 and while the gear wheel may slide upon the said shaft it is constrained to rotate in unison with the same. Shafts 21 are journaled for rotation in the frame 7 and carry at their inner ends gear wheels 22 which mesh with the teeth of the gear wheel 20. Therefore it will be seen that when the wheel 20 is rotated the shafts 21 at the opposite sides of the machine will be rotated in opposite directions.

Vertically disposed shafts 23 are journaled for rotation in the frame 7 and the shafts are preferably arranged in four sets, there being four members in each set. The members of the sets are arranged in rows which extend transversely across the machine and the shafts in the first row are comparatively short while those in the succeeding rows gradually increase in length.

The shafts 23 carry auger blades 24 and each shaft 23 is provided at its lower end with a cutter 25. Bearings 26 are mounted upon the frame 7 and stub shafts 27 are journaled in the bearings 26. The stub shafts 27 are provided at their ends with beveled gear wheels 28 which mesh with

the teeth of similar wheels 29 mounted at the upper ends of the shafts 23.

Sprocket wheels 30 are mounted upon the shafts 21 and sprocket wheels 31 are mounted upon the stubs shafts 27. Chains 32 are trained around the sprocket wheels 30 and 31 and engage the sides of the intermediate sprocket wheel 31. Consequently it will be seen that when the shafts 21 are rotated 10 rotary movement is transmitted by the chains and stub shafts 27 and intermeshing gear wheels 28 and 29 to the shafts 23.

When the machine is positioned over the particular area which is to be plowed or 15 tilled the frame 7 is lowered and at the same time the shafts 23 are rotated whereby the blades 24 and cutters 25 penetrate the soil and cut or break the same. In view of the fact that the shafts 23 are of different length 20 in the different sets of shafts all the soil working elements do not enter the soil simultaneously, consequently some of the soil working elements will operate in the soil at a greater depth than others and this will 25 assure that the soil is properly broken up or worked at the expenditure of a minimum amount of power or force.

From the foregoing description taken in conjunction with the accompanying drawing 30 it will be seen that a soil tilling or plowing machine of simple and durable structure is provided and that the same may be used to advantage and economically for effectually breaking up soil preparatory to planting or other uses.

My sub-soil machine plow can be used on all kinds of soil and enables the soil to be stirred and loosened to a considerable depth and to keep moisture in the ground, 40 and is especially valuable for these purposes in irrigated districts. The machine can be also used in grading roads as it enables the soil to be readily cut up in fine shape for shoveling or scraping.

45 In practice, a suitable clutch is provided on the shaft 4 to enable the machine to be thrown in or out of gear.

Having described the invention what is claimed is:—

1. In a machine of the class described, a 50 main body, a frame mounted on the body for vertical movement, upright shafts carried and mounted for rotation in said frame, said shafts having soil engaging elements at their lower portions, transverse 55 shafts mounted for rotation in the frame and geared to the upright shafts, a vertical guiding shaft mounted in said frame, a gear on said vertical shaft and connected thereto for rotation therewith and vertical movement 60 thereon, means to cause said gear to move vertically with the frame, and means to drive the transverse shafts, said means including a gear engaged with the first named gear.

2. In a machine of the class described, a main body, a frame mounted on the body for vertical movement, upright shafts carried and mounted for rotation in said frame, said shafts having soil engaging elements 70 at their lower portions, transverse shafts mounted for rotation in the frame and geared to the upright shafts, a vertical driving shaft mounted in said frame, a gear on said vertical shaft and connected thereto for 75 rotation therewith and vertical movement thereon, means to cause said gear to move vertically with the frame, means to drive the transverse shafts, said means including a gear engaged with the first named gear, 80 and an engine mounted on the body and connected to said vertical shaft so that said vertical shaft is driven by the engine.

3. A tiller comprising a body, an engine mounted thereon, a frame movably mounted 85 on the body, means for raising and lowering the frame, shafts journaled upon the frame, said shafts being arranged in sets and the sets of shafts being of different lengths, soil engaging elements carried by the shafts and 90 means for rotating the shafts from the engine.

In testimony whereof I affix my signature.
CHALMER DENNY.
